UNITED STATES PATENT OFFICE.

WILL C. NEAHR, OF DENVER, COLORADO, ASSIGNOR TO THE PROTECTIVE SIGNAL MANUFACTURING COMPANY, A CORPORATION OF COLORADO.

ELECTRIC ALARM.

1,187,767.

Specification of Letters Patent. Patented June 20, 1916.

Application filed November 27, 1914. Serial No. 874,220.

To all whom it may concern:

Be it known that I, WILL C. NEAHR, a citizen of the United States, residing at Denver, in the county of Denver and State 5 of Colorado, have invented certain new and useful Improvements in Electric Alarms, of which the following is a specification.

This invention relates to electric alarms, and its principal object resides in providing 10 in an instrument of this character, a circuit controlling device of novel construction which in coöperation with the armature of the electro-magnet breaks the magnet circuit at a determinate point in the movement of 15 the armature toward the magnet coils.

Other objects of my invention reside in the provision of novel means to coöperatively associate the armature with the hammer of the alarm, and in providing an ad- 20 justable and resilient abutment by which the frequency of the hammer strokes, and in consequence that of the vibrating movement 25 of the armature, may be varied at will, and which renders the movements of the hammer equable and mitigates the impact of the contact members included in the circuit controlling device.

A further object of my invention is to 30 provide a housing for the operating mechanism of the alarm which adequately protects the same from dust and moisture without interfering with the movements of the hammer with relation to an exteriorly disposed gong, and still further objects reside 35 in minor details of construction, all of which will fully appear in the following description of my invention with relation to the accompanying drawings in the various views of which like parts are similarly designated, 40 and in which,

Figure 1 represents a face view of the 45 electric alarm in which the greater portions of the gong and the cover of the housing have been omitted to show the operating mechanism within the housing, Fig. 2, a section taken along the line 2—2, Fig. 1, looking in the direction of the arrow drawn across the line, Fig. 3, a face view of the alarm housing without the gong, drawn to a 50 reduced scale, Fig. 4, an enlarged elevation of the circuit-controlling device included in the operating mechanism, Fig. 5, a section along the line 5—5, Fig. 4, and Fig. 6, an enlarged section taken along the line 6—6, 55 Fig. 1.

Referring more specifically to the drawings, the reference character 2 designates the housing of the alarm which comprises a body portion composed of a back plate 3 and a therewith integral, cylindrical side 60 wall 4, and a cover 5.

The housing has in the plane of its back plate, diametrically opposite lugs 6 for its attachment against an upright surface of a suitable support, and the cover has a circumferential flange which is formed to fit snugly around the outer edge of the wall 4 against which the cover is placed, to close the interior of the housing against dirt and moisture.

Bolts 7 extending through axially alined apertures in the cover and the back plate of the housing, serve to securely hold the parts in dust proof connection, and a central axially bored and interiorly threaded boss 75 8 is provided to secure the gong 9 by the use of a bolt 10.

The hammer 12 which in the operation strikes upon the interior surface of the gong, is pivotally mounted upon a lug 13 which 80 projects inwardly from the cylindrical wall of the casing in a plane with the outer edge of the same.

The cover has a peripheral opening in which the lug snugly fits, and the lug has 85 a circumferential flange 14 which engages the lower surface of the cover to effect a dust and moisture proof juncture.

While the lug may be formed integral with the wall of the casing, it is for ease 90 in manufacture, preferably made separately and secured in a recess in the wall by means of a screw 15.

It will be understood without further 95 illustration that strips of suitable packing material may be employed to make a fluid tight fit between the contacting surfaces of the casing and its cover. The cover is reinforced by exteriorly formed radial ribs 16.

The operating mechanism of the alarm 100 which in its entirety is disposed within the housing, comprises an electro-magnet 17, the coils of which are mounted in an upright position upon a bracket 18 which by means of screws, is secured upon the back plate 3. 105

The armature of the magnet consists of a straight bar 19 which is pivotally supported upon an inwardly projecting stud 20 on the plate 3 to engage the poles of the magnet during its downward motion.

The hammer which as hereinbefore explained is pivotally mounted on the lug 13, is by means of a set screw secured upon the exterior end of a short shaft 21 which is 5 rotatably fitted in an opening in the lug and which at its inner end has a laterally projecting crank arm 22.

A wrist 23 projecting from the outer end of the crank arm, engages the outer edge of 10 a lever 24 which at one of its extremities is movably supported in axial alinement with the shaft 21 upon the reduced end portion of a post 25 which is fixed on the back plate 3, and which extends loosely into a socket 15 in the end of the shaft as shown in Fig. 2.

The other extremity of the lever is by means of a link 26 connected with one of the 20 ends of the armature immediately below the same. A resilient abutment 27 which in the operation resists the return movement of 25 the hammer after it has struck the gong, consists of a cylindrical, exteriorly threaded barrel 28 which is longitudinally adjustably mounted in a correspondingly threaded opening of a post 29 secured upon the back plate of the housing.

A head formed at the end of the barrel, facilitates its adjustment, and a jam-nut 30 secured upon the barrel in engagement with 30 the post, secures it in its adjusted positions.

A plunger 31 slidably fitted in the barrel, projects beyond one end thereof to be engaged by the end of the crank-arm on the hammer during its return movement after 35 it has struck the gong.

A stem of reduced diameter at the opposite end of the plunger projects through an opening in the opposite end of the barrel, a transverse pin 32 on the exterior portion 40 of the stem limits the outward movement of the plunger, and a spring 33 coiled around a portion of the stem within the barrel, provides a cushion by resiliently opposing the inward movement of the plunger when it is 45 engaged by the crank arm.

The circuit closing device of the apparatus consists of two contact members 35 and 50 34 one of which is fixed upon the back plate of the housing in insulated relation thereto, and the other one of which is adjustably mounted at the end of a pivoted arm 36 composed of nonconductive material.

The fixed contact member 35 consists of a screw which is secured in an upright position in insulated relation to a bracket 37 on the plate 3, and the other, movable contact member, 34, is composed of an externally threaded barrel 38 which extends through a correspondingly threaded opening in the 60 arm 36, and a plunger 39 which is movably fitted in the barrel and projects beyond the lower end thereof.

The plunger has a threaded stem which 65 loosely extends through an opening in the opposite end of the barrel and which is pro-

vided with a pair of nuts 40 to limit the outward movement of the plunger when its lower end engages the fixed contact member.

A spring 41 coiled around the stem within the barrel deadens the impact between the 70 contacts which at their engaging extremities are provided with conductive tips of durable material, such as platinum or tungsten.

The end of the arm 36 in which its threaded opening is formed, is split and a screw 42 projects through a threaded aperture transverse to the slit, for the purpose of clamping the contact member 34 in its 75 adjusted positions. The arm is pivotally supported at its end opposite to that at 80 which the contact member is secured, to move independently in the direction of the movement of the armature, and for purposes of convenience and simplicity it is mounted upon the end of the same stud 20 85 which supports the armature. The armature and the arm are associated for synchronous operation during a part of the movement of the armature, by means of a pin 43 which extends laterally from the armature into an opening of greater diameter 44 90 in the arm, and a coiled spring 45 which connects the arm with the stationary bracket 37, and which serves to accelerate the return movement of the movable contact member 95 after it has been separated from its fixed correlative.

The electrical connections of the alarm mechanism consist of a wire 46 which connects the magnet windings with the contact 100 member on the nonconductive arm 36, and two wires 47 and 48 which respectively connect the fixed contact member and the other end of the magnet winding with two binding posts 49 and 50 which are secured exteriorly of the cylindrical wall of the housing in insulated relation to the same.

The binding posts serve to connect the alarm mechanism in an electric circuit which in Fig. 1 of the drawings has been 110 shown in conventional symbols, the reference numeral 51 designating the source of electricity, 52 and 53 the conductors of electricity connected at opposite sides thereof, and 54 a circuit breaker of suitable construction.

In the operation of my improved alarm mechanism, the parts are normally, when the line circuit is opened at 54, in the positions illustrated in Fig. 1 in which the armature 120 is separated from the coils of the magnet with its pin extending in the lower portion of the hole of the pivot arm which by its specific gravity and that of the member 34 as well as by the action of the spring 45, maintains the contact members in engagement. The hammer is loosely suspended from the lug 13, and by the engagement of the wrist on its crank with the lower edge of the lever maintains the armature in its above de- 125 130

scribed normal position. Now, when by closing of the line circuit at 54, a current of electricity is circulated through the coils of the magnet, the armature being quickly attracted to the magnetized cores, causes the hammer to strike the gong. During the downward movement of the armature the two contact members remain in engagement until the pin 43 engages the arm 36 at the upper end of its hole, which occurs before the armature has reached the magnet cores. The engagement of the pin with the arm causes the latter to move in synchronism with the armature, with the result that the contact member 34 is separated from the fixed member 35 and the circuit is consequently opened. As soon as the attractive power of the magnet is discontinued, the hammer returns by its specific gravity as well as by its recoil after having struck the gong, to its normal perpendicular position, and in doing so engages the lever 24 with the result that the armature which otherwise would have remained at rest on the magnet cores, is lifted to its normal position. The movement of the armature permits the contact member 34 to reassume its normal position in engagement with the member 35 which again closes the circuit and thereby reenergizes the magnet. The consequent vibrative movement of the armature is kept up as long as the circuit remains closed at 54, and the alarm is thus continuously sounded by the engagement of the hammer with the gong at correspondingly regular intervals. The resilient abutment 27 which is engaged by the crank arm on the hammer prior to the impact of its wrist with the lever 24 prevents violent contact of the members of the circuit-closing device, and at the same time renders the movement of the hammer equable. By adjustment of the position of the barrel of the abutment on the post 29, the movements of the hammer may be regulated to vary their frequency and in consequence that of the vibrative movements of the armature, to any desired degree. The connection of the resilient contact member 34 with the nonconductive arm 36 permits of its adjustment for placing it in its proper position with relation to the fixed contact when the parts are assembled and for taking up wear of the conductive tips of the members.

It will be seen from the foregoing description that by maintaining the magnet circuit in a closed condition, until the armature approaches the end of its downward movement, the amount of current consumed in the operation of the instrument is reduced to the minimum, that by the proper adjustment of the resilient abutment the frequency of the hammer strokes may be varied to a degree which makes it possible to change the instrument from a single stroke alarm to a vibrat-

ing alarm, that these variations in the operation of the instrument are produced solely by regulating the movement of the hammer which is mounted separately for independent movement with relation to the armature, that the resiliency of the movable contact member causes a wiping contact between the two members and prolongs the life of their engaging tips, and that the construction of the housing of the instrument effectively protects the operating mechanism from dust and moisture without interfering with the movements of the hammer relative to the exteriorly disposed gong.

Having thus described my invention what I claim and desire to secure by Letters-Patent is:

1. In an electric alarm, an electro-magnet including an armature pivoted for up and down movement, a lever connected to move with the armature, a loosely suspended, pivoted hammer, a crank-arm supporting said lever, in coöperative connection with the hammer, and an adjustable abutment restricting the movement of the crank arm toward the lever.

2. In an electric alarm, an electro magnet including an armature pivoted for up and down movement, a lever connected to move with the armature, a loosely suspended, pivoted hammer, a crank-arm supporting said lever, in coöperative connection with the hammer, and a resilient, adjustable abutment restricting the movement of the crank arm toward the lever.

3. In an electric alarm, an electro-magnet including an armature pivoted for up and down movement, a lever connected to move with the armature, a loosely suspended, pivoted hammer, a crank arm supporting said lever, in coöperative connection with the hammer, and a resilient abutment to restrict the movement of the crank-arm toward the lever.

4. In an electric alarm, an electro-magnet including an armature pivoted for up-and-down movement, and a circuit-controlling device in the magnet-circuit, comprising a fixed contact-member, a rigid arm pivoted for movement in the direction of the armature-movement, and a resilient contact-member carried on the arm, adjustably in the direction of its movement with the same, the armature having means for separating the members by engagement with said arm after it has passed through a part of its movement toward the magnet core.

5. In an electric alarm, an electro-magnet including an armature pivoted for up-and-down movement, and a circuit-controlling device in the magnet-circuit, comprising a fixed contact-member, a rigid arm pivoted for movement in the direction of the armature-movement, a cylinder adjustably carried on the said arm, a contact-member ex-

tending movably into the cylinder, and a spring in the cylinder to yieldingly oppose inward movement of the movable contact-member, the armature having means for separating the members by engagement with said arm after it has passed through a part of its movement toward the magnet-core.

6. In an electric alarm, an electro-magnet including an armature pivoted for up-and-down movement, and a circuit-controlling device in the magnet-circuit, comprising a fixed contact-member, a rigid arm pivoted for movement in the direction of the armature-movement, a cylinder carried on the

said arm, a contact-member extending movably into the cylinder, and a spring in the cylinder to yieldingly oppose inward movement of the movable contact-member, the armature having means for separating the members by engagement with said arm after it has passed through a part of its movement toward the magnet-core. 20

In testimony whereof I have affixed my signature in presence of two witnesses.

WILL C. NEAHR.
